TOILET VENTILATING APPARATUS AND
VENTILATING METHODStanley H. Churchill, Edmonton, Alberta,
Canada

Application October 25, 1934, Serial No. 750,003

7 Claims. (Cl. 4—213)

The main or primary object of my invention is prompt and complete removal of tainted air and odors (which are inevitable from the use of the generally used toilet fixtures) and to remove these odors and tainted air from the toilet bowl itself as they are formed and to prevent their escape from the bowl into the atmosphere of the toilet room and to do so by apparatus or appliances which commence to function at the time of starting use of the fixture and continue their action for the period the toilet is in use, and to provide apparatus which functions continuously, and which two types of apparatus may be used in combination, or individually, according as the needs of various installations demand. Since my apparatus or system utilizes an electric motor-driven fan or air moving device and the employment of an automatic switch to control or regulate the same, an important feature of my invention is to safeguard persons from electric shock from the switch either while using or cleansing the fixture, and to protect the switch itself from damage or derangement. Other objects and advantages of my invention will be understood from the description or explanation thereof hereininafter given, setting forth what I now regard as most satisfactory embodiments of my invention.

My invention consists in whatever is described by or is included within the terms or scope of the appended claims.

30 In the drawings:

Fig. 1 is a view in vertical section of a building structure such as a hotel, apartment house, or office building, exemplifying an embodiment of my invention in such a case;

35 Fig. 2 is a similar view with parts in elevation of an embodiment of my invention in the form of an individual installation;

Fig. 3 is a perspective view of another individual installation embodiment of my invention where much of the apparatus is exposed or which is an open installation;

40 Fig. 4 is a vertical section through the motor switch;

Fig. 5 is a detail view in perspective of the junction box applied to the seat;

45 Fig. 6 is a detail perspective view of a portion, in section, of the switch shell, the contact bridge bar carrying plunger, and said bridge bar, shown separated;

50 Fig. 7 is a top plan view of a closet bowl in the case of an installation of the switch in the rim thereof;

Fig. 8 is a vertical section on the line 8—8 of Fig. 7.

An important feature of my invention is an installation which has a constant flow of air through channels or conduits in the building or ship, whose toilet accessories call for ventilation or removal of obnoxious smells, which flow may be induced and maintained by what may be termed a master fan situated say on the roof of the building, or the deck, hold, etc. of a ship, and whose induction port is in constant communication with air ducts, pipes or passages preferably provided in the floors and walls or partitions of the structure. And another important feature of my invention in such an embodiment thereof is the provision for each toilet of an air flow inducing device preferably a small electrically driven fan or blower, which takes air from within the fixture and passes it to the stream or current induced or created by the master fan, so that immediately following the action of the individual fan or blower for a unit, air flow from the fixture and its flow to the discharge outlet of the system begins. With a dead air condition in the air flues or conduits, there would necessarily be a lag or retardation of flow from a fixture due to the necessity to set in motion the entire column or body of air leading to the final outlet.

What is shown in Fig. 1 is a rather conventional illustration of a building of several stories with toilet rooms 10, on each floor, the fixtures including a closet 11, of conventional form with a hinged seat 12 and a flush tank 13, and a urinal U. (As I have indicated, my invention is applicable to ships, and what is shown in Fig. 1 may be regarded as typical, regardless of the structure.)

Extending horizontally through each floor is an air duct or channel 14, all of which, say at one side of the building, communicate with a vertical duct or flue 15 that reaches to a point above the roof 16, upon which is placed a fan or air blower 17, such as I have heretofore referred to as a master fan and which at all times is in action, so that constantly or continuously, there is a flow of air through the horizontal ducts or flues and the vertical flues or pipes in the walls of the toilet room to the uptake 15 and through the fan or blower whose exhaust or discharge is thus above the roof of the building. The ducts or channels 14, may be provided with regulating valves, or dampers 14a.

From each fixture 11, an air eduction pipe 18 leads into and upward through the wall or partition 19, and an electric motor driven blower or fan 20, has its induction port connection with the upper end of said pipe and its eduction port communicates with the duct or flue 21, which

passes upward therefrom to the adjacent horizontal flue 14. The electric motor of the fan or blower 20 is in a circuit that includes an automatically operated switch situated to be closed 5 under the weight of one sitting upon the seat and to automatically open when the weight is removed so that the motor runs only during the time the circuit is closed by means of the switch. The construction and installation of the switch 10 which I prefer to use and which I have invented to meet the special requirements of a switch in such a relation are shown in Figs. 4 to 6 and described in detail hereinafter.

No blower or fan 20 is provided for the urinal 15 U, as it is connected by an air duct leading from 14 to a point on its drain just above the water level in the trap, allowing master fan 17 to draw a continuous current of clean air down through drain and thus prevents odor from contaminating 20 toilet room. A similar arrangement is used in the case of urinals attached to the wall (not illustrated).

Besides the multiple installation illustrated in Fig. 1, my invention as to certain of its features may be employed in unit installations such as those shown in Figs. 2 and 3 of the drawings. By unit installation, I mean one where each 25 toilet fixture is not a part of a general system, as in the case of Fig. 1, and may be considered as 30 consisting of the elements included between the closet 11 and the horizontal flue 14 immediately above it, so that the efflux or discharge will not be to such a duct or flue 14, but directly to the air or the outside of the building, as shown in 35 Fig. 2.

Describing what is shown in Fig. 2, there is a closet 11 of conventional construction with a flush tank 13, and I make use of the flush connection between the tank and the bowl for connecting the 40 air eduction pipe 18. This is accomplished by making such flush connection a T 22, the middle arm of which is secured to the bottom of the tank 13, and the horizontal branch being connected at one end of the bowl 11, and at the opposite 45 end by a union coupling 23 to the lower end of the eduction pipe 18. It will be seen that by using the T-fitting, I provide a very simple construction and one where the air connection with the bowl runs directly straight back and thus overcomes difficulties of application or installation which might be created by the position 50 of the bowl and water tank. Such a construction is of particular utility in the adaptation of my invention to old installations already in use, and with the minimum of expense. Thus all the old fixtures are retained intact, or without any alteration merely by the substitution of the T-fitting for an elbow, for example, which the original installation might have between the 55 tank and the bowl.

By running the air eduction pipe 18 into the adjacent wall and then extending it upward therein, the fan or suction device 20, may be placed out of sight and for its protection in a space 24 in the wall just above the top of the tank 13 and thus a cabinet with a hinged sliding or removable front wall 25 provided. Such front wall enables ready access to the suction device when occasion therefor arises. The eduction port of the suction device is connected with the lower end of a vertical pipe 26, passing through the wall and opening above the roof, as shown in Fig. 2, or it could be passed outward through a vertical wall, should the latter be one of the outside walls of the building. There is a con-

nection 27 of rubber or other flexible or yieldable material between the induction and eduction ports of the suction device and the pipes connected therewith to take care of vibration from the running of the motor and to allow of ready disconnection of induction and eduction pipes, and the motor and fan may be placed upon a cushioning pad of rubber or felt.

A concealed installation such as that shown in Fig. 2 may also be employed with the type of 10 closets which have a rear vent at or above the level of the bowl top and which, therefore, may be readily connected with the air eduction pipe. Such a closet with a raised vent is shown on the 15 third floor installation, Fig. 1.

It is to be understood that in the case of new construction or where new fixtures are being installed, they should be preferably of this type, as it has advantages which lend themselves to my 20 ventilating system inasmuch as the rear vent provides a larger, unobstructed passage for the eduction of air from the fixture; the flow of air is not cut off while toilet is being flushed as in the case of the use of the special flush housing 22, which is filled with water until tank 13 is 25 emptied; the larger opening allowing a lower fan speed eliminating hum or fan noise; and the air educed from the rear vent is drier than that drawn through the flush housing connection, eliminating difficulties caused in cold climates in 30 winter due to condensation of this excess moisture in pipes or the formation of ice at the outlet obstructing the air flow.

In Fig. 3, I illustrate an embodiment of my invention which is an open type installation, in 35 that pipes and motor-driven suction device are external to the wall of the room. Thus the air eduction pipe 28 leads from the flush connection between the bowl and the water tank below the latter and then upward alongside the latter and is connected by a flexible coupling with the motor driven suction device 29 placed upon a bracket 30, secured to the wall and the eduction port of the suction device is connected by a flexible 40 yielding coupling to the lower end of the air eduction or exhaust pipe 31, that is supported by 45 brackets from the wall and passes upward through the room ceiling to a suitable outlet point on the exterior of the building. The suction device preferably rests upon a pad of felt or other 50 suitable material to absorb vibration.

The electric switch is shown in Figs. 4 to 6. It includes a shell 32 of bakelite or other material with insulating properties which has an opening at one end from which outwardly projects a flange 33, to lie against the adjacent surface of the seat or other member upon which the switch 55 may be mounted. Said shell is secured firmly in position by retaining screws 32a which pass through holes 32b in the shoulder flange 33, these retaining screws being concealed when the diaphragm and cover plate 41 are assembled in position. At the closed end of the shell embedded in the wall and end and exposed within the same are two stationary contact points or electrodes 34, which respectively by lead wires 35, are connected in circuit with the electric motor of the suction device, the wire connections being on ends of the contacts on the exterior of the side wall of the shell. Loosely mounted within the shell to be readily slidable therein is a plunger 36 which in in a recess at one end has secured to it the bridge contact bar 37, adapted by movement of the plunger towards the contact points 34, to touch the latter and thus close the circuit to the 60 65 70 75 80 85 90 95 100

motor. This contact bridge bar preferably consists of a flat metal spring with raised ends carrying tungsten or other contact faces 37a, reaching beyond the lower face of plunger 36 to which it is secured by a retaining screw as shown. Thus the contact ends touch the contact electrodes 34 and bridge them, at which time current flows through 37. The contact is made by a light springy pressure due to the ends of 37 being raised far enough to touch the electrodes 34 before plunger 36 has been stopped on its downward travel. Normally the contact is broken by the lifting of the plunger to carry the bridge bar away from the contact points 34, when it becomes and remains "dead" electrically, by a coil spring 38, centrally placed within a chamber or recess 39, in the plunger. Such spring bears at one end against the closed wall of the shell which carries a central spring retaining stud 38a, and at the other end against a surface closing the end of the recess 39. The plunger 36 at its upper or outer end is attached to the central portion of a flexible preferably rubber diaphragm 40, which is of greater diameter than the plunger, so that it projects beyond the latter and has its projecting rim or edge secured firmly to the shell 32 between binding or clamping surfaces so that between the latter and the plunger, there is a free portion of the diaphragm which permits the latter to buckle when pressure is applied either by the expanding spring 38 on one side or by opposing pressure on the other as from the weight of a person on the seat. Above the diaphragm and fitting the opening in the shell 32 at that point is a cover plate 41, preferably of metal which lies against the rim or marginal portion of the diaphragm 40, and by means of screws 42, passing therethrough into the shell, clamp or bind such marginal edge against an annular shoulder on the shell. Internally threaded anchor blocks 43, embedded in the shell are provided for engagement by the clamping screws 42.

The central portion of the diaphragm 40 is clamped between the adjacent end of the plunger 36 and the outwardly flanged end of a collar 44 by means of screws 45, which pass through the diaphragm and into internally threaded anchor blocks 46 embedded in the plunger 36, which is preferably of bakelite or other insulating material. The collar 44, passes outwardly from the shell through a central hole in the cover plate 41 and upon its outer end has secured to it a bumper block 47, preferably of rubber, which contacts with the toilet fixture member which supplies the pressure to the bumper to move the plunger to close the circuit through the bridge bar contact 37. Embedded in the bumper block is a thin, flat disc 48 of metal which serves to securely fix to the bumper block a screw 49, that projects from the end thereof next the collar 44, and which engages an internally threaded central hole in the collar 44, to attach the bumper block to the collar. On the side or base of the bumper block opposite the cover plate 41, is secured a bumper plate 50, which has a central hole that receives the reduced end of the collar 44, so that the plate rests upon a shoulder on the collar and thus is the means for transmitting the bumper pressure to the collar and thence to the circuit-closing plunger 36. Another important function of the bumper plate 50, is to contact with the cover plate 41 when the bumper is moved for circuit-closing so that excess pressure will be taken by these two contacting plates and transmission thereof to the inner parts of the switch is pre-

vented which might result in injury thereto. The distance between the two plates is slightly less than the depth or space between the bottom or inner end of the plunger and the closed end of the shell and allowing the points of the bridge contact bar to make a springy contact with the stationary switch points or electrodes 34, so that such parts are never subjected to any heavy and possibly damaging pressure regardless of the force which moves the bumper in circuit-closing movement. The screw 49, of course, secures or holds the bumper plate to the end of the plunger collar 44.

The bumper block has on its outer side a screw-driven slot that reaches to the slotted head of screw 49.

The coil spring 38 has strength or power enough when acting on the seat or movable member of the toilet fixture to lift such member and thus assure movement and holding of the bridge contact bar 37 out of contact with the switch points 34 and thus assure the non-running of the electric motor when the toilet is not in use.

The rubber or elastic diaphragm 40 is to exclude air, moisture and water even if submerged in water, from the interior of such switch mechanism and yet allow free movement of the circuit-closing plunger. To prevent damage to the buckling portion of the diaphragm by any rubbing or cutting action of adjacent parts, a recess 51 is provided adjacent thereto as by bevelling the adjacent surface of the shell wall and outer-edge of flange of collar 44 to an extent that provides ample space for free movement and buckling of the diaphragm and which eliminates any sharp or cutting edges with which the moving or flexing portion of the diaphragm might have contact. The surfaces on opposite sides of the diaphragm which contact therewith for binding or clamping purposes are held by the screws 40 employed with sufficient pressure to make the joints air, dust and water-tight.

Preferably to prevent any turning movement of the plunger 36, within the shell, the plunger may be provided with a vertical groove 52, extending in an axial direction which slidably engages a rib 53, on the adjacent wall of the shell.

As shown in Figs. 3 and 4, the switch is mounted in the underside of the seat and preferably at the left side thereof because that is the side of the seat upon which the weight of the body is thrown in the customary use of the closet, and this assures against accidental opening of the switch by reason of insufficient weight on the seat above the switch as sometimes occurs when switch is on right side, even though the toilet fixture continues in use.

From the switch, two lead wires 35 run through a channel or conduit 54, running internally through the seat from the switch to the hinged end of the seat whereat is a junction box 55. The junction box is placed in a recess in the rear lower side of the seat and includes a block 56 of insulating material such as bakelite, rubber or fiber which is secured in the recess by screws 57. The lead wires 35 are secured to the insulator block 56 by a binding screw or post 58 for each, and to the same binding posts are secured the two current or lead wires 59, which run to the motor.

Besides the two lead wires which connect the switch and the motor, I run a wire 60 from the anchor block 43 adjacent to switch end of conduit 54, which is enlarged at this point for this purpose, soldering wire 60 to the end of the an-

chor block where it appears flush with flange 33. This brings every exposed metal part of switch into contact with wire 60, which runs to a binding post 61, of the junction box from which a 5 wire 62 is carried to a ground and thereby the exposed metal parts of the switch are grounded and thus all possible danger of shock from the high voltage house current which the switch carries is eliminated. Thus even if a person should 10 touch the possibly electrified external metal parts of the switch and at the same time lean against a metal radiator or water pipes, this grounding of the switch would be a perfect safeguard even though such a person might increase the risk by 15 water used in washing the fixture. Further protection from shock is secured by the complete or perfect insulation of the electrodes or contact or switch points, from all other metal parts of the switch and by so mounting bridge contact 20 bar carrying plunger that it has no electrical contacts except when the switch is actually in use. A further safeguard is provided when the switch is located below or on the underside of the seat and is thus hidden and inaccessible to 25 touch, especially when in use. The recess containing the junction box has a cover 63 of insulating material, so that it is protected both physically and electrically, as against short-circuiting, or shocking a user.

30 My junction box is a most advantageous arrangement because it makes the disconnection of the wiring from the seat a very simple matter and has a location or position which assures that the connections shall be safe and inconspicuous.

35 The placing of the wires in the seat is a simple and easily performed operation. After the switch has been installed with the two lead wires and the ground wire attached to the switch parts, the three wires are pulled through the 40 conduit 54 to carry their free ends to the junction box and such ends are secured to the binding posts. The switch terminal ends of the three wires are soldered to the stationary contact points and the cover plate screw anchor 43 before 45 the switch shell is secured in the proper recess in the underside of the seat. The diaphragm cover plate, bumper plate and bumper are conveniently put in place after the switch shell with the parts therein is placed in the seat recess.

50 As shown in Fig. 8, the switch may be installed in the rim of the closet bowl which being of porcelain makes unnecessary the use of an insulating shell of bakelite or the like. In the case of the bowl installation, the stationary switch 5 contacts, the lead wires and the ground wire are molded in the porcelain when the bowl is made as are the cover plate screw anchors. Preferably a junction box would be placed at the rear of the bowl corresponding with the junction box here- 60 inbefore described. Of course, should it be desired, a complete switch construction including a shell of bakelite or other insulating material could be applied to the closet bowl.

65 While I have described with particularity certain features of construction of the very satisfactory embodiments of my invention illustrated in the drawings, it is to be understood that the scope of my protection is not to be confined or restricted to any such special features of construction beyond 70 the express requirements of the following claims and those claims which are not specific

or limited by their recitals to particular features of construction are to be construed as extending to other embodiments of my invention.

Of course, in the case of a large building or 5 ship structure, it may be desirable to divide the structure as far as the installation is concerned into sections or compartments, each having its own master fan, or means for causing a constant air flow through each section or subdivision.

What I claim is:

1. A ventilating system for structures having a plurality of rooms equipped with toilet fixtures, comprising individual air passages leading from respective fixtures, a common air passage to which said individual passages run and having 15 an outlet to the structure exterior, and constantly acting air-current inducing means that cause air flow through such passages to and out of such outlet, supplemental means in the individual passages to cause air flow through them from their 20 toilet fixtures, and means to place such supplemental means in action only when the fixture is 25 in use.

2. A system as in claim 1 further characterized by such means to place the supplemental means in action being automatically started and stopped.

3. A system as in claim 1, in which the individual passages extend vertically, and there are common passages at a plurality of levels and extending horizontally, and a vertical passage leading to the air outlet with which such horizontal passages communicate.

4. A method of ventilating structures having a plurality of toilet fixtures and which is provided with air passages from each fixture to a common passage having an outlet, which includes the act of maintaining a continuous air flow in such passages in the direction of the outlet, and which also includes the act of causing a supplemental air flow in the passages from each fixture only while the fixtures respectively are in use.

5. A system as in claim 1 being further characterized by such means to place the supplemental means in action being automatically started and stopped, and which latter includes an electric switch at the fixture with an exposed current conducting part, and a ground connection from such part.

6. Toilet fixture ventilating apparatus comprising an electrically driven air-moving device, a passage from the fixture to the induction side of said device, an outlet passage from said device, a movable seat for said fixture, an electric switch mounted on the rim of the fixture to be engaged and operated by the seat when weight is applied to the latter, said switch including an exposed metal member, and means for grounding the latter.

7. A toilet fixture ventilator comprising an electrically driven air device with inlet and outlet connections, a circuit, an electric switch mounted on the hinged seat of the fixture at a point between its distal edge and its hinged portion and in said circuit, a junction box applied to said seat at its hinged portion, and wires leading from the switch to the box and from the box to the part of the circuit that includes said air-moving device.

STANLEY H. CHURCHILL. 70
